CLAIM

The ornamental design for a process cartridge for image forming apparatus, as shown and described.

DESCRIPTION

FIG. 1 is a front view of an embodiment of a process cartridge for image forming apparatus;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a front perspective view thereof;

FIG. 8 is a rear perspective view thereof;

FIG. 9 is a front view of another embodiment of a process cartridge for image forming apparatus;

FIG. 10 is a rear view thereof;

FIG. 11 is a top plan view thereof;

FIG. 12 is a bottom plan view thereof;

FIG. 13 is a left side view thereof;

FIG. 14 is a right side view thereof;

FIG. 15 is a front perspective view thereof; and,

FIG. 16 is a rear perspective view thereof.

The broken lines represent portions of the process cartridge for image forming apparatus that form no part of the claimed design.
